UNITED STATES PATENT OFFICE

2,665,026

PARTITIONS FOR BOXES, CARTONS,
AND THE LIKE

Abe Katzman, Bronx, N. Y.

Application November 30, 1949, Serial No. 130,149

3 Claims. (Cl. 217—22)

1

This invention relates to cartons, boxes and the like formed of cardboard, corrugated board and other similar materials and it relates particularly to improvements in partitions for such cartons, boxes and the like to form compartments therein to receive a plurality of articles.

The partition structures for containers of the class referred to usually consist of a plurality of strips of corrugated board or the like which are arranged in intersecting relation by means of notches in their edges so that the partition elements or strips form a grid containing a plurality of square or rectangular compartments roughly conforming to the shape and/or size of the articles to be packed therein. In some cases, a plurality of groups of these partition elements are stacked one upon the other so that a plurality of layers of articles may be packed in a single container.

The partitioning grids are all of the same size and arrangement so that the compartments for receiving the articles are disposed one above the other. If these articles are of any substantial weight, the separator between the several partitioned groups must be quite strong to withstand the weight of the articles.

In the packaging of long necked bottles and the like, for example, liqueur bottles, the usual partition structure, as described above, is not very satisfactory because there is a great deal of waste space left in the container around the necks of the bottles. Any attempt to increase the number of bottles to be packed in a carton having the conventional partition structures has only resulted in the increase in the overall size of the container with even more waste space left therein.

In accordance with the present invention, I have provided a partition structure in which the several partitions making up a grid are positioned asymmetrically so that when several of the grids are superimposed, the compartments between the partition elements are in staggered relation. In this way, the compartments in one partition grid are disposed above the partition elements of a lower grid. By such an arrangement, thin separators may be used between the partition grids, for the weight of the articles in the several compartments are primarily supported by the partitions instead of the separators.

Moreover, in cartons for long necked bottles and the like, it is possible, through the use of staggered and suitably spaced partition strips, to use up a very substantial proportion of the waste space by packing the articles in two layers with the necks of the uppermost group of bottles extending downwardly between the upwardly extending necks of the lower layer or group of bottles. In this way, a 25 per cent savings in space can be obtained, or, more specifically, for

2

example, it is possible to pack a dozen bottles in a carton designed to accommodate nine bottles.

For a better understanding of the present invention, reference may be had to the accompanying drawings, in which:

Fig. 1 is a plan view of a carton containing a partition structure embodying the present invention which is especially adapted for packaging bottles and the like; and

Fig. 2 is a view in section taken on line 2—2 of Fig. 1.

The invention will be described with reference to the packing of certain specific articles but it will be understood that the kind of articles packed in the boxes and cartons having the new partition structure is immaterial. The invention will further be described with reference to conventional corrugated board boxes or cartons although the new partition structures are equally useful in boxes formed of other materials.

An asymmetrical or offset arrangement of the partitions is used in boxes or cartons for bottles and the like, especially bottles having necks which extend about half the overall height of the bottle, for example liqueur bottles, bottles for toilet preparations and the like.

A typical carton for packaging such bottles and the partition structures of therefor is shown in Figs. 1 and 2. The carton illustrated in Figs. 1 and 2 is square and normally would be so partitioned as to accommodate three rows of three bottles each or a total of nine bottles in such a square carton.

By using partition structures of the type described hereinafter, it is possible to package 12 bottles in a carton of exactly the same size, thereby increasing the effective capacity of the carton by 25%. As shown in Figs. 1 and 2, the carton 20 has upper and lower grid elements

35 21 and 22 which are identical in structure, but, as shown, are reversed end for end, for a purpose to be described. The uppermost partition grid 21 is made up of two spaced apart parallel partition elements or strips 23 and 24 and two additional pairs of transverse elements or strips 25, 26, 27 and 28. The partitions 23 and 24 are spaced apart a distance equal to about one third of the width of the box 20 and the partition 25 is spaced from the left-hand ends of the partitions 23 and 24 a distance about equal to the spacing between the partitions 23 and 24. The partitions 25, 26, 27 and 28 extend on opposite sides of the partitions 23 and 24 a distance equal to about the spacing between the partitions 23 and 24.

The partitions 25 and 26 are spaced apart about one third of the distance between the partitions 23 and 24. The partitions 26 and 27 are spaced apart a distance about equal to the spacing between the partitions 23 and 24 so that six com-

partments 29 are provided by the grid which are substantially square in horizontal section to receive rather closely the individual bottles B to be packed therein.

The partitions 27 and 28 are spaced apart about the same distance as the spacing between the partitions 25 and 26 and the partition 28 is spaced from the right-hand ends of the partitions 23 and 24 a distance about equal to the spacing between the partitions 27 and 28, thereby providing three rows of small compartments 30, 31 and 32, having a total width substantially equal to the width of one row of compartments 29.

The lowermost grid 22 is made up in exactly the same way, but, as shown in Figs. 1 and 2, this grid is reversed end for end so that the narrow compartments 30 and 31 directly underlie the mid-portions of the larger compartments 29 in the upper grid 21. The smaller compartments 30 and 31 of the upper grid are adapted to receive the necks of the bottles disposed in large compartments in the lower grid 22 while the narrow compartments of the lower grid 22 are adapted to receive the necks of the inverted bottles in the upper rows of compartments 29. In order to hold the bottles in position, a separator 33 is placed between the upper and lower grids 21 and 22, this separator being provided with twelve holes 34 therein in approximate alignment with the centers of the compartments 29, 30 and 31.

Inasmuch as the lower grid 22 contains six large compartments 29, as does the upper grid, six bottles may be placed in the rows of large compartments in the lower grid and six bottles may be placed in the compartments 29 in the upper grid in inverted position with the necks of these bottles passing through the openings 34 in the separator and being received in the correspondingly aligned smaller compartments 30 and 31. In this way, all of the bottles have their bases and their necks housed in separate compartments so that they are amply protected. Moreover, the new partition structure permits twelve bottles to be packed with very little waste space in a container designed normally to accommodate only nine of these bottles. The saving in space and convenience in packing of the bottles will be most apparent.

It will be understood that the invention as described above is adapted to the packing of many different types of articles and affords better protection to the packed articles than prior structures.

While the invention has been described with reference to cartons for a dozen bottles, the invention is easily adapted to the packaging of many more bottles, and, in fact, instead of only two layers of bottles, as illustrated in Fig. 2, the carton may be modified to include four or more layers of bottles, each layer containing fewer or more than six bottles.

It will be seen that the weight of the uppermost layer of bottles is carried almost directly by transverse partitions so that there is little danger of collapse of the partition structure with resulting damage to the bottles.

The form of the invention described herein should be considered as illustrative of the invention and not as limiting the scope of the following claims.

I claim:

1. A container for a plurality of articles comprising a receptacle, a first group of partitions including a first pair of partitions extending along

and within said receptacle in spaced apart, substantially parallel relation, second and third pairs of partitions intersecting and substantially perpendicular to the first pair of partitions, said second pair of partitions being spaced from the ends of said first pair a distance greater than the space between said second pair, said third pair of partitions being spaced from said second pair a greater distance than the space between said third pair to form, with said first pair of partitions, rows of compartments therebetween alternately of greater and lesser cross-sectional area, a separator resting on said first group of partitions and having openings therethrough in alignment with said compartments, and a second group of partitions intersecting to form compartments therebetween corresponding to the compartments formed by said first, second and third pairs of partitions, the compartments between said second group being offset with respect to the compartments between the first group to position the compartments of lesser cross-sectional area of the second group in alignment with the openings in alignment with the compartments of greater cross-sectional area between the first group of partitions.

2. The container set forth in claim 1 in which the compartment at one end of each row of compartments is of smaller cross-sectional area than the compartments at the opposite ends of said rows.

3. A container for a plurality of articles comprising a receptacle, a first group of partitions including a first pair of partitions in said receptacle in substantially parallel relation, second and third pairs of partitions intersecting and substantially perpendicular to the first pair of partitions; said second and third pairs of partitions dividing the spaces between said first pair of partitions and the walls of said receptacle into rows of compartments alternately of greater and lesser cross-sectional areas, the compartments having lesser cross-sectional areas being approximately one-third as large as the compartments of greater cross-sectional area, a separator resting on said first group of partitions in a plane substantially at right angles to the planes of said first group of partitions, a second group of partitions like the first group of partitions and including first, second and third pairs of partitions, the second and third pairs of partitions of said second group being offset and parallel with respect to the second and third pairs of partitions of said first group to position the compartments of lesser cross-sectional area of the second group above and in alignment with the compartments of greater cross-sectional area of said first group, and said separator having openings therein positioned substantially centrally of the compartments formed by the first and second groups of partitions.

ABE KATZMAN.
